CLAIM

The ornamental design for a tool support, as shown and described.

DESCRIPTION

FIG. 1 is a perspective view of a tool support according to the present invention;

FIG. 2 is an elevated front view of the tool support of FIG. 1;

FIG. 3 is an elevated rear view of the tool support of FIG. 1;

FIG. 4 is a right side view of the tool support of FIG. 1;

FIG. 5 is a left side view of the tool support of FIG. 1;

FIG. 6 is a top view of the tool support of FIG. 1;

FIG. 7 is a bottom view of the tool support of FIG. 1; and, FIG. 8 is a perspective view of the tool support of FIG. 1 supporting a tool rendered in broken line.

The broken lines in FIG. 8 merely illustrate the environment for the tool support of the present design and form no part of the claimed design.
